CLAIM

The ornamental design for a martial arts training device, as shown and described.

DESCRIPTION

FIG. 1 is an isometric showing of a martial arts training device showing my new design;

FIG. 2 is a rear elevation thereof;

FIG. 3 is a top view thereof;

FIG. 4 is a side elevation thereof, both sides being generally the same except that one is the mirror image of the other;

FIG. 5 is a bottom view thereof; and,

FIG. 6 is a frontal elevation thereof.

The broken line portions of the FIG. 1 drawing are for illustrative purposes only and form no part of the claimed design.
